UNITED STATES PATENT OFFICE.

HANS WESTRUD, OF VIRGINIA, MINNESOTA.

DESIGN FOR A BALLOT BOX.

Application filed June 2, 1924. Serial No. 9,774. Term of patent 14 years.

To all whom it may concern:

Be it known that I, HANS WESTRUD, a citizen of the United States, residing at Virginia, in the county of St. Louis and State of Minnesota, have invented a new, original, and ornamental Design for Ballot Boxes, of which the following is a specification, reference being had to the accompanying drawing, forming part thereof.

I claim:

The ornamental design for a ballot box shown.

HANS WESTRUD.
